UNITED STATES PATENT OFFICE.

LOREN D. HART, OF NORA SPRINGS, IOWA.

WASHING-MACHINE.

SPECIFICATION forming part of Letters Patent No. 679,147, dated July 23, 1901.

Application filed January 19, 1900. Serial No. 2,002. (No model.)

To all whom it may concern:

Be it known that I, LOREN D. HART, a citizen of the United States of America, residing at Nora Springs, in the county of Floyd and State 5 of Iowa, have invented an Improved Washing-Machine, of which the following is a specification.

My object is to provide improved mechanism for detachably and adjustably connecting a clothes-pounder to a tub to be reciprocated and swung about in the tub to pound and wash clothing spread about in the tub and submerged in water.

My invention consists in a handle fixed to 15 a pounder and detachably and adjustably connected with a lever, an adjustable post for supporting a lever, an adjustable device for detachably fastening the post to a tub, a lever pivotally connected with the post, and 20 a clamp pivotally connected with the lever for adjustably and detachably connecting the pounder-handle with the lever, constructed and combined as hereinafter set forth, pointed out in my claims, and illustrated in 25 the accompanying drawings, in which—

Figure 1 is a perspective view of my invention, showing how it can be applied to a tub as required for practical use. Fig. 2 is 30 an enlarged detail view showing how the lever is pivotally connected with a portion of the lever-support. Fig. 3 is an enlarged detail view showing how the handle of the pounder is adjustably and detachably connected with the lever.

35 A designates a pounder provided with a handle D. A wooden handle is fitted in the socket B and has a shoulder that engages the top edge of the socket. A series of transverse notches f in the central portion of the 40 handle are adapted to engage rivets in a clasp pivotally connected with the lever. The lever is a straight wooden bar H, and H² is a guide-bar. The rounded ends of the lever H and bar H² are pivoted to a clip J, made 45 of sheet metal, and the other end of the bar H² is connected with the central portion of the lever H by means of a straight metal strap J², and also pivotally connected with a clasp adapted for detachably and adjustably 50 connecting the handle D with the bar H² for operating the handle and pounder by means of the lever H.

A clasp K, consisting of a single piece of sheet metal bent double, is pivoted at its top end to the upper end portion of the bar H² to 55 fasten the handle D of the pounder, as shown in Fig. 3, in such a manner that the lever can be vibrated to carry and operate the pounder in a perpendicular position in different portions of the tub. The lower rivet S² extends 60 through the clasp and also through the lever H, and the upper rivet extends through the clasp and the end of the bar H², and both the rivets S² are adapted to enter notches f in the face of the handle D. To fasten the 65 handle D in the clasp K, a screw-bolt K² is extended through the mating parallel ends of the clasp and a winged nut placed on the screw for compressing the clasp on the handle, as shown Fig. 3. 70

To pivotally connect the lever and pounder with a tub, I have provided a wooden post L, that has a bore and metal ferrule at its top to serve as a socket, and a shoulder m at its central portion and inside face adapted to 75 engage the top edge of a tub, and an integral inclined downward extension m', adapted to overlie the outside of a tub, and an exterior shoulder or enlargement n at its lower end, and a vertical bore in said extension through 80 which a clamp-iron r is extended and adjusted by means of a thumb-nut r' on its screw-threaded top end. The lower end of the clamp is in the form of a hook r'', adapted to engage the bottom of a tub, as shown 85 in Fig. 1. The post L may thus be readily attached to tubs differing in height by means of the clamp-iron r being adjustable.

A U-shaped support for the lever is preferably made of a metal tube S. It has one of 90 its ends connected to the lever by means of the clip J, through which it is extended and secured by means of keys s' or in any suitable way, and its other end is simply inserted in the bore of the post L, having freedom to 95 swing only horizontally.

In the practical operation of my invention when detachably and adjustably connected with a tub the pounder A may be readily moved about over clothing in all parts of the 100 tub or tubs and pressed down upon the clothing by seizing the free end of the lever or the top of the handle that carries the pounder, and when the downward pressure is applied

a contractile spring connected with the lever H and the bar H², as shown in Fig. 1, is stretched, but will resume its normal position when the pressure is relaxed, and in so doing 5 lift the pounder above the clothing, as required, to lessen the labor and facilitate the rapid succession of downward pressures upon the clothing. A downward stroke of the lever stretches the spring, as required, to store 10 power therein that will lift the part H and H², that is pivotally connected with the handle D of the pounder A. Every downward pressure of the lever and pounder will cause 15 air in the pounder to be confined and compressed and to be forced out with water through the meshes of textile fabrics in the tub, as required, to loosen and remove dirt therefrom without rubbing and straining the fiber and wearing and damaging the articles 20 subjected to such action of the machine.

Having thus described the construction and operation of my invention, its practical utility will be obvious to persons familiar with the art to which it pertains, and what 25 I claim as new, and desire to secure by Letters Patent, is—

1. In a washing-machine, a lever pivotally connected with a post, a bar pivotally connected with the same post and connected with

the lever by means of a strap pivoted to the 30 end of the bar and the central portion of the lever, a clasp pivoted to the end portion of the bar by means of a rivet, a screw-bolt extended through the ends of the clasp for tightening the same, a rivet extended through the 35 lower portion of the clasp and the lever and a handle having notches in one of its faces to admit the rivets extended through said clasp, arranged and combined to operate in the manner set forth for the purposes stated. 40

2. In a washing-machine attachment, a straight upright having a bore in its top portion for pivotally connecting a lever-support and a shoulder at its bottom to engage the top edge of a tub, an inclined extension below said shoulder adapted to overlie the outside face of a tub, a shoulder at the bottom of said inclined extension and a vertical bore in the lower end portion, a clamp device consisting of a rod having a hook at its lower 45 end to engage the bottom of a tub extended through said bore and a nut screwing on its top end, arranged and combined in the manner set forth for the purposes stated. 50
